CLAIM

The ornamental design for a push/pull door sign, as shown and described.

DESCRIPTION

FIG. 1 is a top front perspective view of a push/pull door sign showing my new design;

FIG. 2 is a top rear perspective view thereof;

FIG. 3 is a front elevation view thereof;

FIG. 4 is a rear elevation view thereof;

FIG. 5 is a right elevation view thereof, with the left elevation view being a mirror image thereof;

FIG. 6 is a top plan view thereof, with the bottom plan view being a mirror image thereof; and,

FIG. 7 is a top front perspective view thereof, shown in an environment of use.

The broken lines shown in the drawings depict portions of the article and environmental structure that form no part of the claimed invention.
